UNITED STATES PATENT OFFICE.

ELMER NORUM, OF HALLOCK, MINNESOTA.

PROPELLER FOR SLEIGHS.

Application filed November 19, 1925. Serial No. 70,131.

This invention relates to motor sleighs and the like, and particularly to the propellers thereof.

The general object of the invention is to provide an improved propeller designed to be driven by an engine mounted upon the sleigh, this propeller being so constructed that it not only has a rotary motion against the snow but a sliding motion as well relative to the snow so that soft snow which would otherwise tend to gather upon the propeller will be swept off.

A further object is to provide a propeller for a motor sleigh consisting of two or four cylinders driven by the engine on the sleigh, these cylinders being disposed at such an angle to the line of draft that when they revolve they will have also a sliding movement, the cylinders both propelling the sleigh and assisting in carrying the load, and in this connection to provide a motor sleigh with cylindrical propellers disposed at an acute angle to the line of draft to thus reduce any retarding action of the cylinders, the angle of the cylinders to depend upon the amount of load carried. The smaller the load, the greater the speed due to ability to decrease the angle between the cylinders and the longitudinal axis of the sleigh to thus secure a greater amount of sliding motion for the cylinders per revolution than where a greater angle is used.

Other objects will appear in the course of the following description.

My invention is illustrated in the accompanying drawings, wherein:—

Figure 1 is a top plan diagrammatic view of a sleigh showing my new propeller therefor;

Figure 2 is a sectional view through a propeller;

Figure 3 is a top plan view of the gearing whereby four propellers may be driven from the same drive shaft, each of these propellers being inclined relative to the line of draft.

Referring to these drawings, it will be seen that I have illustrated diagrammatically a frame, designated generally 10, and shown as of an approximately triangular shape, this frame being pivotally supported at 11 upon front runners 12. These runners are steering runners and may be steered in any suitable manner and I have illustrated a simple handle 13 for this purpose, it being understood, however, that more complicated steering means might be used.

Disposed upon the sleigh frame and supported thereby is the engine 14, which may be of any suitable type as, for instance, an internal combustion engine having a drive shaft 15. The rear end of the sleigh is formed to support two cylinders, each being designated generally 16, the shaft 17 of which intersects the rear end of the driving shaft and is driven therefrom by means shown as beveled gears conveying power to the shafts 17 and driving them in the same direction in any suitable manner, the gears being designated generally 18. The outer ends of the shafts 17 are supported in suitable bearings.

The cylinders consist of a plurality of radial arms or spokes 19, these arms being held in spaced relation by rings 20. The spokes 19 project through these rings and the extremities of the spokes carry upon them the longitudinally extending blades or skis 21, each of these skis being slightly curved upon its outer face transversely to the length of the ski and extending rearward and outward relative to the direction of motion of the cylinder.

It is to be particularly noted from Figure 1 that the axes of these cylinders 16 are disposed at an acute angle to the longitudinal axis of the sleigh. I have found that if the propellers are disposed with their blades at right angles to the longitudinal axis of the sleigh that there is no sliding action of the propellers, and where there is any tendency for the machine to pick up speed and move more rapidly than the propelling means, the propelling means acts to hold it back because there is a drag of the propelling means in center. My arrangement of the cylinders with their skis permits the skis or cylinders to slide somewhat as they rotate, and I have found that the angle at which these propelling cylinders are to be placed depends entirely upon the use to which the sleigh is to be put.

The smaller the load, the more acute the angle to which they can be set, and vice versa, and where the cylinders are disposed at quite an acute angle the skis are found to slide more per revolution of the cylinder. This secures a greater speed than where the propelling cylinders are disposed at an angle nearer a right angle.

The particular advantage in placing the cylinders at an acute angle to the line of draft is to get a sliding motion which pro-

vents any snow from sticking to the cylinders, or in other words sticking to the skis and to the space between the skis and packing thereon in case of mild weather. Where 5 heavy loads are to be carried, four cylinders or propellers might be used, as illustrated in Figure 3, in which the four shafts 17 of the corresponding cylinders are each disposed at an acute angle to the line of 10 draft and each of these cylinders is driven by a shaft 17, these shafts in turn being driven from the common driving shaft 15 extending from the engine. The width and 15 the length of the skis, that is the skis 21, varies according to the load they are intended to carry.

As illustrated in Figure 1, the shaft carries a beveled gear wheel 18^a which meshes with a beveled gear wheel 18^b on one of the 20 shafts 17, both of the shafts being geared to each other by the gear wheel 15. In Figure 3, the shaft 15 carries the beveled gear wheel 18^a which meshes with a beveled gear wheel 22 mounted upon one of the shafts 25 17, and the shaft 15 also carries a beveled gear wheel 23 meshing with the oppositely disposed shaft 17. Also mounted upon the shaft 15 is the beveled gear 24 which meshes with one of the rear shafts 17 and the other 30 rear shaft 17 is driven by means of a beveled gear wheel 25 mounted upon the shaft 15. Thus all of the several shafts 17 are driven in the same direction and at the same rate of speed.

35 I do not wish to be limited to any particular form of vehicle to which these propellers might be applied, as it is obvious that they may be applied to pleasure sleighs or load-carrying sleighs, busses, trucks or the like. 40 Neither do I wish to be limited to the use of the propellers on the rear end of the vehicle, as they might be placed on the front end of the vehicle and accomplish the same result, provided, of course, there was proper steering 45 mechanism in the rear, these propellers being disposed at an angle to the longitudinal axis of the machine less than a right angle. Neither do I wish to be limited to the exact power transmitting mechanism 50 illustrated, as this might be modified in many ways without departing from the spirit of the invention as defined in the appended claims.

I claim:—

55 1. A motor-propelled sleigh having a pair

of cylindrical propellers at one end, the propellers being formed with blades and the propellers being disposed with their axes at an angle to each other and at less than a right angle to the longitudinal axis of the 60 sleigh.

2. A self-propelled sleigh having a pair of cylindrical propellers at one end, the propellers being disposed with their axes at an angle to each other and at an acute angle 65 to the longitudinal axis of the sleigh, each propeller including a circumferential series of longitudinally extending blades.

3. A self-propelled sleigh having a pair of cylindrical propellers at one end, the propellers being disposed with their axes at an angle to each other and at an acute angle to the longitudinal axis of the sleigh, each propeller including a circumferential series of 70 longitudinally extending blades, each propeller including a plurality of series of spokes radiating from the axle, and longitudinally extending blades carried by said spokes.

4. A self-propelled sleigh having a pair 80 of cylindrical propellers at one end, the propellers being disposed with their axes at an angle to each other and at an acute angle to the longitudinal axis of the sleigh, each propeller including a circumferential series of 85 longitudinally extending blades, each propeller including a plurality of series of spokes radiating from the axle, and longitudinally extending blades carried by said spokes, each blade being slightly convex 90 transversely upon its outer face and each blade extending outward and rearward relative to the direction of motion of the propeller.

5. The combination with a sleigh body 95 having front steering runners and an engine, of propelling means for the sleigh body comprising a pair of cylinders disposed at the rear end of the body and driven from said engine, the cylinders having their axes disposed at an angle to each other and at an acute angle to the longitudinal axis of the sleigh, each cylinder comprising spokes radiating from the corresponding axle, circumferential members holding said spokes in 100 fixed relation, and longitudinally extending blades mounted upon said spokes.

In testimony whereof I hereunto affix my signature.

ELMER NORUM.
